United States Patent Office

Des. 178,583
Patented Aug. 21, 1956

178,583

WATCH BAND OR SIMILAR ARTICLE

Kurt Speck, Palisades Park, N. J., assignor to Jacques Kreisler Manufacturing Corporation, North Bergen, N. J., a corporation of New Jersey

Application September 21, 1955, Serial No. 38,029

Term of patent 3½ years

(Cl. D45—4)

FIG. 1

FIG. 2

FIG. 3

FIG. 4

Fig. 1 is a plan view of a watch band or similar article showing my new design;

Fig. 2 is an enlarged edge view showing one of the two terminal members (as shown on the right in Fig. 1) and a section of the connecting elements;

Fig. 3 is an end view of the terminal member as seen when viewed as indicated in Fig. 2; and

Fig. 4 is a section taken on the line 4—4 of Fig. 2.

I claim:

The ornamental design for a watch band or similar article, substantially as shown.
